UNITED STATES PATENT OFFICE.

VANDIVER J. VAN HORN, OF CHICAGO, ILLINOIS.

SEWING-MACHINE.

1,143,795.

Specification of Letters Patent. Patented June 22, 1915.

Application filed May 15, 1914. Serial No. 838,808.

To all whom it may concern:

Be it known that I, VANDIVER J. VAN HORN, a citizen of the United States, residing in Chicago, in the county of Cook and State of Illinois, have invented certain new and useful Improvements in Sewing-Machines, of which the following is a specification.

The present invention relates to a sewing machine for making a double-chain seam, being a seam made up of two threads, one of which is sometimes called the needle thread but is herein called the "top thread", being the thread that lies along the top or right side of the work when the seam is completed, and the other of which is called by various names, depending upon the character of the stitch, but is herein invariably called the "bottom thread" and lies along the "wrong" or bottom side of the work when the seam is completed. The top thread passes from a spool to and through the eye of the needle and thence through the work to looping mechanism while the bottom thread passes from a second spool and thence through suitable guides or eyes to the looping mechanism, the latter being of such construction and having such mode of operation, and co-operation with the needle that loops are formed in both threads and the loops of both threads are interlooped or interlocked with each other to form the stitch.

Nothing is herein claimed for the stitch, *per se*, as the invention of this application relates to the mechanism by which the stitch is formed.

Generally stated, the object of the invention is to provide an improved sewing machine for making a seam of this class.

More particularly stated, one object of the invention is to provide a sewing machine, adapted to make a double-chain stitch, in which a rotatable member is made use of for doing more or less of the work of handling both threads in the process of making the stitch.

Another object of the invention is to provide a sewing machine of the class described with a rotatable member, which is rotated continuously in one and the same direction, with means whereby it not only takes the loop of the top thread and holds it while some subsequent step in the process of forming the stitch is taking place, but in addition forms a loop in the bottom thread, draws it through the loop of the top thread

and holds said loop of the bottom thread in such position that the needle will pass through it with unerring certainty and form another loop in the top thread in position to be taken by the rotating taker, the first-named loop of the top thread having meanwhile been passed off of the heel of the loop taker in rear of the needle so that it will embrace the aforesaid loop of the bottom thread.

Another object of the invention is to positively control the movements and location of the various parts of the thread, at all critical points throughout the successive cycles of operations that must be carried out in the running of a seam—this latter term being herein used to comprehend a continuous series or succession of individual stitches. This positive control is to avoid all random or haphazard movements of any part of the thread with a consequent possibility of mislocation, at critical points which mislocation would result in skips or misses in the forming of interlocking of the so related loops of the two threads by which the stitches are locked so as to prevent the seam from being unraveled or pulled out.

Another object of the invention is to provide a double-chain-stitch sewing machine with improved stitch forming mechanism of such construction that at each stitch-forming operation an excessive length of thread will not be drawn from the respective spools to form an excessive amount of slack at a point between the last stitch and the spool, thereby dispensing with the need for a take-up, which in machines of this class as heretofore constructed is necessary for taking up the excess slack thread that is drawn into the loop.

Another object of the invention is to provide improved mechanism for drawing the loops of the bottom thread into close contact with the bottom side of the work, and drawing the interlocking portions of the loops of the two threads well into the work, to the end that the seam shall be as nearly flush with the opposite faces of the work as practicable.

Another object of the invention is to provide improved, simplified and more durable mechanism by which the loop taker for taking the loops of the top thread is connected with, and disconnected from its driver.

Another object of the invention is to provide, for transmitting movement from a

shaft to a loop taker, means of such construction that in a gang machine, or a machine having a plurality of needles arranged side by side, and a loop taker appropriate to each needle, the transmitting means of any particular loop-taker may be applied to or removed from the shaft laterally, without the necessity for first removing all of the loop-takers and their driving means between the particular loop-taker and the one at either end of the gang.

Another object of the invention is to provide, for engaging and disengaging the loop-taker, a slide operated directly by a simple stationary eccentric which co-operates with the main shaft of the machine.

With these and other objects, that will appear hereinafter, in view the invention consists in the features of novelty that are hereinafter described with reference to the accompanying drawings which are hereby made a part of this specification.

Preliminarily it may be observed that the running of a seam involves a succession of cycles of operations that must be carried out in forming each stitch of the succession of stitches of which the seam is made up, and each of these cycles of operations finds the parts in certain relative positions at certain points or stages which, starting at any arbitrarily selected point in the cycle may be designated as the first position, second position, third position, etc. For convenience and clearness of description these designations have been adopted in the following description, and in the drawings, starting arbitrarily with the needle up and at its highest point, as the first position.

In the drawings: Figure 1 is an end face view, on a small scale, of the head of a sewing machine with the parts in the first position,—the needle up and at its highest point of travel. Fig. 2 is an enlarged sectional elevation of the stitch forming mechanism with the parts in the third position, the plane of the section being approximately indicated by the line 2—2, Fig. 5. Fig. 3 is a view similar to the upper portion of Fig. 2 but with only the upper portion of the face plate broken away, and the parts in the fourth position. Fig. 4 is a view similar to Fig. 3 with the parts in the fifth position, some of the parts shown in Fig. 3 being omitted to avoid mere duplication. Fig. 5 is a sectional elevation with the parts in the second position, the section being taken on irregular planes which are partly vertical and partly axial and more or less inclined to the vertical. Fig. 6 is a sectional elevation of the parts shown in the upper position of Fig. 5, with the parts in the third position. Fig. 7 is a plan view of those parts that are below the line 7—7, Fig. 5, with the parts in the second position. Fig. 8 is a plan view of those parts that are below the line 8—8,

Fig. 6, with parts in the third position. Fig. 9 is a rear elevation on a larger scale of the parts that are directly instrumental in forming the stitch, in the first position. Fig. 10 is a plan view thereof with the work omitted, the second position of the parts being indicated in this figure by dotted lines. Fig. 11 is a view similar to Fig. 9, with the parts in the third position. Fig. 12 is a plan view thereof with the work omitted. Fig. 13 is a view similar to Figs. 9 and 11 with the parts in the fourth position. Fig. 14 is a plan view thereof with the work omitted. Fig. 15 is a view similar to Figs. 9, 11 and 13 with the parts in the fifth position. Fig. 16 is a plan view thereof with the work omitted. Fig. 17 is a view on a still larger scale, of the same parts in the sixth position but viewed from the left hand end of the machine. Fig. 18 is a view similar to Fig. 17 showing the parts in the seventh, and about to come to the first position. In the drawings the several portions of the threads are somewhat distorted from their accurate courses, for the sake of clearness. Fig. 19, is a perspective view of the race ring and the cast off finger. Fig. 20 is a perspective view of the loop-taking member. Fig. 21 is an elevation of a combined cam and eccentric for imparting a compound movement to the deflecting finger of the looper for the bottom thread. Fig. 22 is a perspective view of an adjustable plate having eyes for guiding the bottom thread to the looper. Fig. 23 is a section of the deflecting finger of the looper and the means for imparting to it the desired compound movement. Fig. 24 is a perspective view on an enlarged scale of a portion of a seam made by a machine embodying the invention.

The machine of the present invention is similar in some respects to the machine shown and described in my co-pending application filed on April 13, 1914, Serial No. 831,527, and while all of the several features of the present invention are applicable to a double-chain machine, still some of its features are equally applicable to single-thread or single-chain machines. This is particularly true of the means for driving the "loop-taker", and temporarily disengaging the loop-taker from its driving mechanism at such times and points as will allow the loop-taker to enter and withdraw from the loop or pass completely through it, according to the construction and operation of the stitch-forming mechanism, whether the loop-taker be in the form of a shuttle, which is passed through the loop, or a device for simply temporarily holding the loop while some other operation is being performed. And there may be still other features of the machine herein shown and described that will be found to be useful in

types of machines other than the one herein shown and described, and I therefore reserve for myself the exclusive right to embody the several novel features of the invention in machines of any type in which they may be found to be useful.

The machine shown has a loop-taker, 1, in the form of a segment of a ring, which occupies loosely, so as to be capable of being easily and freely moved therein, about its mechanical axis, a circular groove or race, 2, formed in the inner surface of a ring, 3, which is fixedly secured to the bed plate of the machine-head as by screws, 4. The groove or race is formed by counterboring the ring, 3, and the cylindrical wall of this counter bore forms a guide for confining the loop-taker against random movement radially, relatively to its axis. The bottom of the counterbore results in a shoulder which restrains the lateral movement of the loop-taker in one direction—inward—while it is similarly restrained in the opposite direction—outward—by a face plate, 5, which is secured to the ring, 3, as by screws, 6, the face plate being provided with circular openings, 7, through which the heads of the screws, 4, are accessible. The face plate has on its inner face a circular rib, 8, which fits snugly but loosely within the loop-taker, 1, and within this rib the face plate has a circular recess, 9, to provide clearance for the movement of certain parts hereinafter described. The face plate, 5, the rib, 8, and the race ring, 3, are all cut away opposite the throat of the machine to permit the free and unobstructed play of the needle and the several parts of the threads which extend downward from the under side of the work to the looping mechanism.

The face plate has a centrally located circular opening through which the main shaft, 10, of the machine passes, the plate being thickened around the opening as shown at 11, to form an adequate bearing for the shaft, 10, and also to provide for the formation of an eccentric, 12; which occupies the recess, 9, and the end of which lies close to the outer face of a disk, 13, as also does the inner face of the rib, 8. The disk, 13, is nonrotatively secured to the shaft, 10, and has in its outer face a diametrical groove, 14, in which fits, so as to be capable of free reciprocation therein, a slide, 15, which is confined to strictly rectilinear movement by the straight sides of the groove, 14.

The slide carries at its opposite ends cylindrical pins or plungers, 16, and 16^a, respectively, which are radial with respect to the axis of the driving disk, 13, and are adapted to be alternately and reciprocally thrust into or through, or completely withdrawn from sockets, 17 and 17^a, respectively, with which the loop-taker, 1, is provided at diametrically opposite points. These sockets preferably

take the form of perforations extending completely through the loop-taker radially and the length of the plungers, 16 and 16^a, and the amplitude of movement of the slide, 15, are such that when the slide is moved to the limit of its permitted movement in one direction one of the plungers will be completely withdrawn from its socket, (as shown in the case of the plunger, 16,) and therefore out of engagement with the loop-taker, 75 while the other will extend completely through its socket and so as to project more or less beyond the periphery of the loop-taker, if desired, to permit which the race, 2, may be grooved as shown at 2^a or some other provision made.

The slide is provided with two transverse abutments located upon diametrically opposite sides of its transverse middle and also opposite diametrically opposite points on the shaft, 10, and these abutments are preferably in the form of ribs, 18, and 18^a, which cross the slide at right angles, and project into a recess, 9, where they lie in the plane of the eccentric, 12. The slide has through it a longitudinal slot, or opening, 19, through which the shaft, 10, passes freely, without contact, and the slide is preferably constructed of two similar parts each of which has a part, 15^a, which is longer than the diameter of the shaft, and overlaps and lies against the other part, being secured thereto as by a screw, 20, the two parts, in all of their features, being exact duplicates and therefore reversible and interchangeable. 100 By forming the slide of two separable parts it can be placed upon or removed from the shaft laterally, so that where there is a plurality of slides on the same shaft any one of them can be removed and replaced without disturbing any of the others.

The periphery of the loop-taking ring has in it a groove, 21, extending through a sufficient number of degrees to afford clearance for the end of the needle, and into this groove projects a cast off finger, 22, which is made of a piece of plate metal and the shank of which fits tightly in a groove or slot cut in the race ring, 3, in which it is held firmly, but so as to be capable of adjustment, by a screw, 23, which is tapped into the race ring and has an enlarged head that engages the shank of the finger so as to hold it firmly in its adjusted position. The end of the finger is beveled or dressed off in such manner that as the bottom thread is moved laterally, in the direction of rotation of the loop-taker, which is indicated by the arrow placed upon it, (*i. e.*, clockwise when viewed as in the drawings) and comes in contact with the finger, it will be thrown out radially with respect to the ring—toward the underside of the work and against the front side of the needle as shown more clearly in Fig. 17. This cast off finger is 130

for the purpose of freeing in succession the loops of the bottom thread from shoulders, 24, that are carried by the loop-taker near its heel end, 1^b, and are substantially radial to the loop-taker. These shoulders are preferably formed by cutting down the walls of the opposite sides of the groove, 21, of the loop-taker near its heel end, the cutting down being graduated so that the walls of the groove will gradually increase in height from the bottoms of the shoulders to a point in advance of them, as shown at 25.

The bottom thread, B, upon leaving the spool which is not shown but which may be located in any convenient or desired place, passes through suitably arranged guiding eyes to and through an eye, 26, on a plate, 27, having through it a slot 28, through which passes a screw, 29, by which the plate is secured to the face plate, 5, so that the plate, 27, and consequently, the eyes carried by it may be adjusted with relation to the position of the needle path. From the eye, 26, the thread passes into an eye or passage way, 30, one end of which opens at the end of a cylindrical plug, 31, rotatively fitting in a socket in a tubular arm, 32, of a block, 33, and the other end, 30^a, of which opens at the periphery of said plug opposite an opening, 34, with which the cylindrical arm, 32, is provided. From this latter end of the passageway, 30, the thread passes to and through a second eye, 35, with which the plate, 27, is provided, and thence directly or indirectly (as the case may be) to the last nascent stitch, a that has been made but not yet "set" in the work. The walls of the various eyes and passages through which the bottom thread passes, engage the thread and by frictional contact therewith hold it under greater or less tension, but for greater uniformity of this tension the thread preferably passes through a tension device as indicated at, b, which may be of any known or desired construction, and located in any convenient position. It will be understood that when the point of the needle, N, leaves the work on its upward movement, this last nascent stitch will be directly in the line of travel of the needle, but during the interval while the needle is moving downward from its uppermost position and until its point again reaches the work, the forward feeding of the work will take place. This will bring the last nascent stitch aforesaid one step in the rear of the position of the line of travel of the needle, as shown in Figs. 2, 3, 4, 7, 8, 10, 12, 14, 16 and 17. The plate, 27, should have been so adjusted that the eye, 35, is slightly in rear of the plane of the loop-taker in which the needle lies so that when the work shall have been fed forward one step, or a distance equal to the length of one stitch, the portion, B¹, of the bottom thread will entwine upward from

the eye, 35, to the last nascent stitch, a, in the work and at a greater or less angle to the aforesaid plane in which the needle lies, depending upon the distance the work is fed forward, thus bringing this portion B¹, to the position herein arbitrarily called the first position. While the portion B¹, of the bottom thread, B, is in this first position a deflecting finger, 36, which is a part that assists in forming the loops in the bottom thread moves in the direction of the arrow placed upon it in Fig. 10 from the position shown by full lines in said figure to the position indicated by dotted lines in said figure and shown by full lines in Figs. 4, 7, 12, 14, 16 and 17, i.e., close to the inclined portion of the portion B¹, of the bottom thread—the second position.

It may here be stated that the finger, 36, has near its end a shoulder, 37, formed on a reentrant angle, resulting in a notch, and beyond this shoulder a slender tongue, 38, formed in continuation of the rear of the finger, 36, and projecting beyond the shoulder, 37.

From this second position the finger, 36, moves directly inward, as indicated by the arrows, in Figs. 5, 7 and 9, to the position shown in Figs. 2, 6, 8, 11, and 12, this being the third position. This endwise movement of the finger, 36, deflects the portion, B¹, of the thread and brings a portion of it to bear upon the sloping portions, 25, of the walls of the groove, 21, of the loop-taking ring, 1, in advance of the shoulders, 24, as shown in Figs. 2, 6, 11 and 12, this being the third position. The deflecting finger, 36, then, for a time, remains idle and out of contact with the bottom thread until it is returned to the position shown in Figs. 9 and 10,—its first position or starting point. Meanwhile the loop taker continues to move on, having been in constant motion during all of the above described movements of the finger, 36, and during all of this period a loop, T¹, of the top thread, T, will partly surround and be held by the loop-taker, 1. At the first position the thread of this loop, T¹, extends from the eye of the needle downward through the work, thence under the loop-taker and thence upward through the work at the last made and set stitch of the seam.

As the loop-taker moves onward from the third position the shoulders, 24, will engage the portion, B¹, of the bottom thread and form a loop, B², therein, and will also carry a portion of this loop, B², through the loop, T¹, bringing a portion of it, while still engaged by the shoulders, 24, in front of the line of travel of the needle, as shown in Figs. 3, 4 and 16. As the needle continues to descend its point will enter the loop, B², (and the groove, 21, of the loop-taker) and as the loop taker continues its movement

the loop, B^2 , will be enlarged until it comes in contact with the cast off finger, 22, as shown in Fig. 16, whereupon it is cast off radially with respect to the loop taker and 5 upward toward the work. The needle having by this time entered it it will be caught and held by the needle as shown more clearly in Fig. 17. The portion, T^2 , of the top thread which is carried by the needle will 10 form a second loop which as the needle moves upward will be opened up or distended and will be entered by the beak, 1^a, of the loop-taker, 1, and handled in the same manner as the loop, T^1 . This is indicated in 15 Fig. 18, but the actual relations of the parts are somewhat distorted in this figure for the sake of brevity and clearness of description.

It may here be stated that at about the 20 instant the loop, B^2 , is being cast off by the cast off finger, 22, the heel 1^b, of the loop taker escapes from the loop, T^1 , and to facilitate the easy movement of the thread the loop-taker is rounded off in both directions—*i. e.*, longitudinally and transversely. At this instant the needle is still moving downward. In fact, the loop, T^1 , must escape before the point of the needle reaches the inner surface of the loop-taker, else said 30 loop will strike the needle and cannot pass behind it as shown in Fig. 17. The drag on the thread produced by this downward movement of the needle will draw up that portion of the top thread which passes upward through the work, as a result of the preceding stroke of the needle, and thus tighten or “set” the preceding stitch, b .

Fig. 17 shows the sixth position with loops of the two threads that enter into the nascent 40 stitch formed and interlooped but in more or less distorted relation to each other as neither the nascent stitch nor the stitch next preceding it has been tightened or “set”. This setting is done in part by the needle 45 and in part by the deflecting finger of the bottom-thread looper. As the needle continues to move downward from the position shown in Fig. 17 it will draw down that portion, t , of the top thread which extends 50 upward from the eye of the needle to and through the work and occupying the opening through the work that has just been formed by the downward movement of the needle. This will draw toward the needle 55 that portion, t^1 , of the thread that lies along the top of the work and extends to the next preceding stitch, being a continuation of that portion, t^2 , of said preceding stitch which extends through the work and is a 60 continuation of one side of the loop, T^1 . This will contract the loop, T^1 , and draw it well up against the “wrong” or bottom side of the work. In thus contracting and drawing up the loop, T^1 , the two sides of 65 the loop, B^2 , of the bottom thread are like- wise drawn up against the wrong or bottom side of the work, but the loop, B^2 , will be left slack and (when the needle moves upward until its point is withdrawn from said loop, B^2) extending around the two sides 70 of the loop, T^1 , of the top thread.

The deflecting finger, 36, has a peculiar compound movement which, starting with the parts in the first position, first carries the finger, laterally (see Figs. 7, 9 and 10) 75 toward the path of travel of the needle, to bring the front side of its extension tongue, 38, in contact with, or at least in close proximity to the inclined portion of the portion B^1 of the bottom thread (see same figures). 80 In producing this lateral movement of the finger, its stem, 39, is given a partial rotation about its axis which occupies a plane which is axial with respect to the shaft, 10. The shaft 10 has nonrotatively secured to it 85 a cam-block, 40, which has a circumferential groove, 41, lying in a plane which forms an acute angle to a plane perpendicular to the axis of the shaft, 10, and resulting in parallel cam surfaces, 42 and 43, which are also 90 parallel with the plane of the groove, 41. This groove is occupied by a ring 44 which for convenience in assembling and disassembling is preferably formed in halves secured together by screws as indicated at, 45. 95 The opposite faces of this ring have loose, sliding contact with the cams, 42, 43, and the ring has a socket, 46, in which the lower end of the stem, 39, fits and is fixedly secured as by a screw, 47. The stem, 39, is 100 positively prevented from any rotary movement about the axis of the shaft, and consequently the angular position of the ring relatively to the axis of the shaft will continually change as the shaft rotates. The 105 ring will have a compound movement which is the resultant of its movement about an axis which passes through the axis of the stem, 39, and is radial to the axis of the shaft, 10, and its movement about a second axis which is perpendicular to the first. The stem, 39, is prevented from being carried about the axis of the shaft, 10, by reason of the facts that it passes loosely through, so as to be capable of both rotary and end- 110 wise movement therein, an opening through the above-mentioned cylindrical block, 31, and also through the tubular arm, 32, of the block, 33, for which purpose said arm has lateral openings, 48, which permit the free 115 lateral movement of the stem, 39, back and forth in the axial plane of the shaft, 10, as a result of the oscillation of the ring, 44, about its second aforesaid axis of movement. The block, 33, is bodily movable back and 120 forth upon a supporting pin, 49, which projects rigidly from the face plate 5 and is parallel with the axis of the shaft, 10. This movement of ring, 44, about its second aforesaid axis of movement moves the finger, 36, 125 130

endwise so that after reaching the position indicated by dotted lines in Fig. 10 and shown by full lines in Figs. 7 and 12, it will be moved inward endwise as indicated by 5 the arrows placed upon it in Figs. 5, 6, 7 and 9, to the position in which it is shown in Figs. 6, 8, 11, 12, 13, 14, 15 and 16. This will deflect the portion, B¹, of the bottom 10 thread so that a portion of it will cross the loop taker, 1, in advance of the shoulders, 24, as shown most accurately in Fig. 12, Figs. 8, 12 and 14 being similar in this respect excepting that they show successively different 15 positions of the parts of the threads due to the continued movements of the loop-taker and the needle. The resultant of these lateral and endwise movements of the finger, 36, will be a movement of its outer end in a substantially elliptical path. But in addition 20 to these movements the stem-end of the finger is given a bodily up and down movement. This is accomplished by making that portion of the cam block, 40, which forms the bottom of the cam groove, 41, in the 25 form of an eccentric, 50, so disposed that its major axis will throw the ring, 44, upward as the cam, 43, is throwing the finger, 36, inward, as indicated by the arrows in Figs. 5, 6, 7, 9, 11, 13 and 15. As the finger, 36, 30 is also confined to movement about the axis of the plug, 31, which axis is constantly shifting toward and away from the loop taker, 1, as the block, 33, slides back and forth upon its supporting pin, 39, the end of 35 the finger, 36, will be caused to duck down behind the loop taker, as shown in 11, 13 and 15. As a result of all of these factors the finger has a bodily up and down movement, a lateral oscillatory movement about 40 an axis which lies in a vertical plane, and a lateral oscillatory movement about a horizontal axis which latter axis is parallel with the stand of the loop taker and laterally movable toward and from said plane. The 45 result of all of these movements is a movement of the active part of the finger (the shoulder 37) in a circuitous path which lies in a plane that passes outside of the loop taker and is at an angle to its axis of movement. 50

The means for accomplishing the objects of the invention and producing the various movements above particularly described are susceptible of many modifications and variations and I, therefore, desire to have it understood that the invention in its broader aspects is not limited to the details of construction above particularly described and shown in the drawings.

60 What I claim as new is:—

1. In a sewing machine, means for forming a double-chain-stitch having, in combination, a rotatable member, means for rotating it continuously in one and the same direction, and mechanism having parts op-

eratively arranged with relation to said rotatable member and coöperating therewith to form loops in both the top thread and the bottom thread, said rotatable member being adapted to engage and hold the loops of the top thread and having means for engaging the loops of the bottom thread and drawing them through the loops of the top thread. 70

2. In a double-chain-stitch sewing machine, a rotatable member having a beak arranged to engage and temporarily hold a loop of the top thread, and having means for engaging the bottom thread when the top thread is so engaged by the rotatable member, whereby as said rotatable member advances, a loop is formed in the bottom thread and interlooped with the aforesaid loop of the top thread. 80

3. In a sewing machine, means for forming a double-chain-stitch having, in combination, a rotatable member, means for rotating it continuously in one and the same direction, and mechanism having parts operatively arranged with relation to said rotatable member and coöperating therewith to form loops in both the top and bottom threads, the means for forming the loops in the two threads being so arranged relatively to each other that the loops of one thread are passed through and interlocked 90 with the loops of the other thread. 95

4. In a double-chain-stitch sewing machine, the combination with a needle, means for operating it, a rotatable member and means for rotating it, said member having a beak arranged to enter a loop of the top thread formed by a previous stroke of the needle, said member being so shaped that it distends the loop sufficiently to permit its own passage through it and said member having means for engaging the bottom thread, of means for holding the bottom thread when so engaged whereby as said rotatable member advances, after engaging the bottom thread it will form a loop there-in and draw said loop through the aforesaid loop of the top thread and in a position where it surrounds the path of the needle, the movements of the needle and revolute member being so timed that the point of the needle, in descending, enters and passes through the loop of the bottom thread, and thereafter the loop of the top thread escapes from the rotatable member and surrounds 105 the two sides of the loop of the bottom 110 thread. 115

5. In a double-chain-stitch sewing machine, the combination with a rotatable member, in the form of a segmental ring, and means for revolving it about an axis concentric with it, said rotatable member having a beak arranged in position to enter a loop of the top thread formed by the preceding stroke of the needle, said member being so shaped that it distends the loop of the 120 125 130

top thread sufficiently to permit its own passage through it and said member having in advance of its heel end a shoulder adapted to engage the bottom thread, of means for engaging the bottom thread when so engaged whereby as said rotatable member advances it will draw a portion of the bottom thread forward, laterally, thereby forming therein a loop and drawing said loop into the afore-
10 said loop of the top thread, to a position where it surrounds the path of the needle, the movements of the needle and revolute part being so timed that the point of the needle, in descending enters and passes through the loop of the bottom thread carrying with it a portion of the top thread which forms a second loop in position to be entered by the beak of the revolute member.

6. In a sewing machine, means for forming a double-chain-stitch, having in combination, a rotatable member, means for revolving it continuously in one and the same direction, said member being arranged to enter, distend and temporarily hold the loops of the top thread and having means for engaging the bottom thread and means for engaging the bottom thread when so engaged, whereby as the rotatable member advances loops are formed in the bottom thread, and carried to a position surrounding the path of the needle.

7. In a sewing machine, means for forming a double-chain-stitch, having in combination, a rotatable member, means for revolving it continuously in one and the same direction, said member being arranged to enter, distend and temporarily hold the loops of the top thread and having means for engaging the bottom thread and means for engaging the bottom thread when so engaged, whereby as the rotatable member advances loops are formed in the bottom thread, and interlooped with the loops of the top thread.

45 8. In a sewing machine, means for forming a double-chain-stitch, having in combination, a rotatable member, means for revolving it continuously in one and the same direction, said member being arranged to enter, distend, and temporarily hold the loops of the top thread and having means for engaging the bottom thread and means for engaging the bottom thread when so engaged, whereby as the rotatable member advances loops are formed in the bottom thread, drawn through the loops of the top thread and carried to a position surrounding the path of the needle.

60 9. In a double-chain-stitch sewing machine the combination with a rotatable member and means for rotating it continuously in one and the same direction, said member having a beak so arranged relatively to the path of the needle that as said member revolves its beak will enter a loop of the top

thread formed by a previous stroke of the needle, said rotatable member being adapted to distend said loop sufficiently to pass completely through it and hold it distended until its heel escapes from the loop, said member having near its heel end shoulders presented forward, means for disposing a portion of the bottom thread across the periphery of said member in advance of the shoulders, and means for holding said portion of the bottom thread in this position until, during the forward movement of said member, the shoulders engage it, form a loop therein and draw said loop into the aforesaid loop of the top thread and past the path of the needle, the movements of said needle and member being so timed that the loop of the top thread escapes from the heel of said member, whereupon the loop of the top thread escapes past the needle and the loop of the top thread surrounds the two sides of the loop of the bottom thread in rear of the needle.

10. In a double-chain-stitch sewing machine, means for forming loops in the top thread, a member for taking and temporarily holding said loops, said loop-taking member being movable in a circular path, and means for moving it, said loop-taking member having a beak arranged to enter and take a loop of the top thread, said loop-taking member having also, in rear of its beak, a forwardly presented shoulder and having clearance for the point of the needle, in combination with means for laying a portion of the bottom thread across the loop-taking member in advance of said shoulder, whereby as the loop-taking member advances said shoulder will engage that portion of the bottom thread which lies across the loop-taking member, and means for engaging the bottom thread whereby as the loop-taking member advances said shoulder will form a loop in the bottom thread and carry it to a position surrounding the path of the needle.

11. In a double-chain-stitch sewing machine, means for forming loops in the top thread, a member for taking and temporarily holding said loops, said loop-taking member being movable in a circular path, and means for moving it, said loop-taking member having a beak arranged to enter and take a loop of the top thread, said loop-taking member having also, in rear of its beak, forwardly presented shoulders and having also a circumferential groove continuing between said shoulders and affording clearance for the point of the needle, in combination with means for laying a portion of the bottom thread across the loop-taking member in advance of said shoulders, whereby as the loop-taking member advances said shoulders will engage that portion of the bottom thread which lies across the loop-taking member.

- the loop-taking member, and means for engaging the bottom thread whereby as the loop-taking member advances said shoulders will form a loop in the bottom thread 5 and carry it through the loop in the top thread and to a position surrounding the path of the needle.
12. In a double-chain-stitch sewing machine, means for forming loops in the top 10 thread, a member for taking and temporarily holding said loops, said loop-taking member being movable in a circular path, and means for moving it, in combination with means for laying a portion of the bottom thread across said loop-taking member, said loop-taking member having means for engaging that portion of the bottom thread which is laid across it as aforesaid, whereby as the loop-taking member advances a loop is 15 formed in the bottom thread and carried to a position surrounding the path of the needle.
13. In a double-chain-stitch sewing machine, means for forming loops in the top 20 thread, a member for taking and temporarily holding said loops, said loop-taking member being movable in a circular path and means for moving it, said loop-taking member having a beak arranged to enter and take a loop of the top thread, said loop-taking member having also in rear of its beak forwardly presented shoulders and having also a circumferential groove continuing between said shoulders and affording 25 clearance for the point of the needle, in combination with means for laying a portion of the bottom thread across the loop-taking member in advance of said shoulders, whereby as the loop-taking member advances said shoulders will engage that portion of the bottom thread which lies across the loop-taking member, as aforesaid, means for engaging the bottom thread whereby as the loop-taking member advances a loop will be 30 formed in the bottom thread and carried to a position surrounding the path of the needle and a cast off finger projecting into said groove and adapted to cast the loop of the bottom thread off of said shoulders in 35 advance of the needle.
14. In a sewing machine the combination with a needle and a member adapted to engage and hold the loop formed by the needle, said member being rotatable in a circular 40 path and having forwardly projecting shoulders adapted to engage and form a loop in the bottom thread of a cast off finger arranged in front of the path of the needle for engaging said loop and casting it off of said shoulders.
15. In a double-chain-stitch sewing machine the combination with a rotatable loop-taking member adapted to engage a loop formed in the top thread, of a deflecting 45 finger adapted to engage and position va- rious portions of the bottom thread and means for operating said deflecting finger, said operating means having means for moving said finger back and forth laterally and means for moving it back and forth longitudinally, whereby its position with relation to the loop of the top thread is changed, both with relation to the plane of said loop and a plane perpendicular thereto. 70
16. In a double-chain-stitch sewing machine means for forming a loop in the top thread, a loop-taking member adapted to engage and temporarily hold said loop, and means for guiding and holding the bottom thread in combination with a deflecting finger adapted to engage the bottom thread and means for operating said finger, said operating means having means for moving said finger laterally toward and from the plane of the loop of the top thread and 75 means for moving it endwise in a direction substantially parallel with said plane. 80
17. In a chain-stitch sewing machine, a needle, means for operating it, a thread deflecting finger located beneath the bed plate 90 and behind the needle, in position to engage the needle thread, in combination with means for operating said deflecting finger, said operating means having means for moving the finger laterally toward and from the needle 95 and means for moving said finger longitudinally in a direction which is transverse to the stitching line.
18. In a chain-stitch sewing machine, the combination with a needle, means for operating it, a finger located beneath the bed plate and in rear of the needle in position for engaging and deflecting the needle thread, means for moving said finger laterally toward and from the needle about a 100 given center, and means for moving said finger longitudinally in a direction which is lateral with respect to the axis of said center. 105
19. In a chain-stitch sewing machine the combination in a thread deflecting mechanism of a finger, means for moving it laterally about one axis, means for shifting said axis whereby the finger is moved radially relatively to the axis aforesaid and longitudinally relatively to itself, and means for moving the finger laterally relatively to the axis last aforesaid. 110
20. In a chain-stitch sewing machine a finger for deflecting a thread having, in combination, a stem movable longitudinally and also laterally and radially relatively to its axis, a ring to which said stem is attached, a cam block having a groove occupied by 115 said ring and a shaft about which said cam block is rotated, the cam groove aforesaid occupying an angle to the axis of said shaft and that portion of the cam block which forms the bottom of the cam groove being eccentric to the axis of the shaft. 120
- 125
- 130

21. In a chain-stitch sewing machine, the combination with a thread deflecting finger, of means for operating it, said means having a shaft, a cam block non-rotatively secured to said shaft and having a groove occupying a plane forming an angle with said shaft and resulting in cam surfaces on opposite sides thereof, that portion of the cam block which forms the bottom of the groove being eccentric with relation to the axis of the shaft, a ring occupying said groove, a stem carrying said finger and attached to said ring, a part through which said stem passes so as to be capable of both longitudinal and rotary movement relatively thereto, and means for supporting said part and permitting of its bodily movement in a direction parallel with the shaft.

22. In a chain-stitch sewing machine, the combination with a loop-taking member movable in a circular path, of means for moving it, said means for moving it having a rotatable member, a slide movable radially with respect to said rotatable member and an eccentric engaging said slide, said eccentric being fixed relatively to the rotatable member.

23. In a chain-stitch sewing machine, the combination with a loop-taking member movable in a circular path, of means for moving it, said means having a rotatable member, a slide carried by said rotatable member and movable radially relatively thereto, and a fixed eccentric engaging said slide, said rotatable member having means for confining said slide to movement in a plane perpendicular with the axis of the rotatable member.

24. In a chain-stitch sewing machine, the combination with a loop-taking member movable in a circular path, of means for moving it, said means having a rotatable carrier disk provided with diametrical guide-ways lying in the plane perpendicular to the axis of said disk, a slide engaging said diametrical guide-ways and a fixed cam engaging said slide for moving it diametrically relatively to the carrier disk as the latter rotates.
